UNITED STATES PATENT OFFICE.

HARRY WALLACE LAWRENCE, OF DENVER, COLORADO.

ELECTRICAL-WIRING KNOB.

No. 907,251.

Specification of Letters Patent.

Patented Dec. 22, 1908.

Application filed June 10, 1908. Serial No. 437,696.

To all whom it may concern:

Be it known that I, HARRY WALLACE LAWRENCE, a citizen of the United States of America, residing at the city and county of Denver, and State of Colorado, have invented a new and useful Electrical-Wiring Knob, of which the following is a specification.

My invention relates to improvements in electric wiring knobs, and the objects of my invention are: first, to provide a combined wire supporting and terminal end securing non-conductive knob. Second, to provide a two part knob adapted to be used as a clamping support for electric wires, and also as a securing knob for the ends of electric wires. And third, to provide a simple, strong, combined electric wire clamping and fastening knob, that is adapted to be secured to objects by a clamping screw extending through its axial center.

I attain these objects by the mechanism illustrated in the accompanying drawings, in which:

Figure 1, is a front elevation of the improved electric wiring knob. Fig. 2, is a side elevation of the same. Fig. 3, is a vertical, sectional view on the line 3—3 of Fig. 2. Fig. 4, is a vertical sectional view on the line 4—4 of Fig. 1. Fig. 5, is a plan view of the base of the knob. Fig. 6, is a plan view of the under side of the cap. And Fig. 7, is a plan view of the device, showing the manner of securing the wire around the terminating knob, and wrapping it upon itself.

Similar letters of reference refer to similar parts throughout the several views.

Referring to the drawings, the numeral 1, designates the base portion of my knob. This base portion comprises a short stem portion of any suitable non-conductive material, preferably porcelain. I preferably make my improved knob round in shape, although it may be made of any other form or shape. The bottom of this base portion, is flat, and is preferably provided with a recess 2, at its center, in order that the remaining ring portion will bear squarely against the wood or other material to which it is secured. Through the axial center of the length of this base portion, a clamping - screw - receiving aperture 3 is formed, through which a clamping screw 4 extends loosely. This base portion is provided with a cap portion 5, through the axial center of which an aperture 6 is formed, through which the clamping screw 4 also passes. The cap receiving

end of the base portion of my knob is provided with a raised base portion 7, of smaller diameter than the base, diametrically through the center of which extends a recess 7^A, which is preferably of V-shape, and the cap is provided with a depending base portion 8, of smaller diameter than the cap, which is provided with a depending V-shaped lug 8^A that fits into the recess 7^A in the top of the base portion, and thus centers the cap on the top of the base, and at the same time prevents the cap from turning on the base when the clamping screw is tightened against the cap, when screwing the screw into wood to secure the knob into wire supporting position. On one side of the base, and also on the same side of the cap, I form projecting lug portions 9 and 10 respectively, which are arranged to register opposite to one another and are arranged relative to each other so as to stand a slight distance apart, and in the opposing surfaces of each projecting lug I form recesses 11 and 11^A, preferably curved recesses, the surfaces of which are formed into a plurality of teeth 12, which are preferably arranged at an angle to the length of the recess, and the teeth of the recess of the cap are preferably arranged at an opposite angle to the angular direction of the teeth of the recess in the base, as these teeth are not so apt to cut into the insulation of the wires and weaken them when the wire is clamped tight in the aperture formed by these recesses through the base and cap, when the cap is clamped tight against its base by the clamping screw. A wire securing groove 13 is also formed around the base and cap, and partially between the base and the cap, and in circumferential alinement with the wire receiving and clamping recesses. The top of the cap is preferably countersunk deep enough to permit the head of the screw to extend below the surface of the cap.

The operation of my improved wire supporting and tying knob is as follows: The cap is placed on the base, and the base is placed against the wood or other screw receiving material to which the knob is to be secured. The clamping screw 4 is then inserted through the cap and base, and is screwed into the wood or other material to hold the base portion fixed to the wood, but to leave the cap with enough movement on the screw away from the base to insert a wire into and extend it through the toothed aper-

ture formed between the cap and its base by the curved recesses 11 and 11^a. As soon as the wire is inserted in the toothed aperture, it is drawn tight from its fastened end, and 5 then the screw is screwed into the wood until the head of the screw engages the cap and forces it down onto the base, causing its toothed recess 11^a to engage and clamp the wire rigidly in the toothed recess 11 of the base, with pressure enough to cause the 10 teeth of these recesses to sink into the insulating covering of the wire, and thus rigidly secure the wire against any slipping movement through the knob. The knobs are thus attached at intervals to the walls, 15 ceilings, and casings of rooms and other portions of buildings and other things wherever electric wires are to be run, and wherever a wire terminal is, a knob is placed and the end portion of the wire is clamped in the knob and 20 its end is run around the circumferential groove of the knob until it meets the clamped portion of the wire, around which it is twisted, and is thus secured. The wire is thus secured 25 to non-conductive insulating knobs, to which it is rigidly secured against any possibility of accidental displacement.

Having described my invention, what I claim as new and desire to secure by Letters 30 Patent, is:

1. A non-conductive electric wire supporting knob, comprising a base, a cap fitting on said base, a screw aperture through said cap and base, a screw extending loosely through 35 and beyond said cap and base and adapted to secure said base to wood or other screw penetrating articles, and to clamp said cap to said base, a projection on one side of said cap and a similar projection on the side of 40 said base registering opposite the projection of said cap, a recess in the face of each projection beyond the body of said knob registering opposite each other and adapted to form a wire receiving and wire clamping and 45 gripping recess laterally to one side of the body of said knob, a plurality of angularly arranged wire gripping teeth in the recess of the projection of said base and a plurality of teeth in the recess of the projection of said 50 cap arranged at an opposite angle to the teeth of the recess of the projection of said base, and a wire receiving groove extending from said recesses circumferentially around the body of said knob at the registering 55 edges of said cap and base.

2. An insulating electric wiring knob, comprising a base portion and a cap portion, each of which is provided with an axial aperture extending through it in alignment with 60 the other apertures, means including a depending oblong lug portion on said cap, and

a recess in said base, arranged to prevent rotative movement of said cap on said base, laterally projecting lug portions on said cap and base registering opposite each other and 65 projecting beyond the body of said knob, a toothed aperture formed partially in the lateral projection of said cap and partially in the projecting lug of said base, said toothed aperture being positioned outside of the body of said knob and arranged to partially surround a wire, and an annular groove formed partially in the meeting edges of said cap and base extending around said knob from one end of said toothed aperture in said 70 lateral lug portions to its opposite end.

3. An insulating non-conductive knob for supporting electric wires, comprising the base containing an annular bearing ring at its supporting end, a diametrically arranged 80 recess in its wire supporting end, a projecting lug portion on one side of said base portion substantially level with its top portion, provided with a curved wire receiving recess adapted to receive a predetermined size of 85 electric wire, said curved recess being provided with angularly arranged wire gripping teeth, a groove extending around the top edge of said base, and a screw receiving aperture extending through the axial center of 90 said base, with a cap provided with a depending lug fitting the groove in said base and adapted to prevent said cap from turning on said base, a laterally projecting lug portion on one side of said cap registering 95 opposite to the lug on said base, provided with a toothed recess that is positioned beyond the body portion of said cap and that is arranged to register with said toothed wire holding recess of said base, a groove extending 100 around the edge of said cap from one end of said toothed recess to its opposite end, and arranged to register opposite to the groove in the top edge of said base, said circumferential groove around said cap and base being a continuation of the toothed groove in the 105 projecting lug portions of said cap and base, a clamping screw receiving aperture through the center of said cap registering in alignment with the aperture in said base, and a 110 cap clamping and base fastening screw extending through said cap and base, said toothed aperture being arranged to surround a wire and said clamping screw causing said cap to clamp the wire to said base.

In testimony whereof I affix my signature in presence of two witnesses.

HARRY WALLACE LAWRENCE.
